UNITED STATES PATENT OFFICE

2,283,562

VAPORIZING APPARATUS

William Lister, Chicago, Ill.

Original application May 27, 1939, Serial No. 276,253. Divided and this application December 21, 1939, Serial No. 310,455

15 Claims. (Cl. 123—133)

My invention is concerned with a novel means and method for vaporizing or volatilizing different grades of oil so that they can be used in an engine without the necessity of replacing the carburetor or similar mechanism when the kind of fuel is to be changed.

To this end, it consists of a novel vaporizing mechanism associated with means for heating the oil before it reaches the vaporizer and a thermostat which can be set to turn off or reduce the action of the heating means at different temperatures, so that there will be no danger of raising the temperature of the particular oil used beyond its flash point, and thereby causing an explosion before it is vaporized and forced into the associated engine to be exploded to furnish power in the customary manner.

To illustrate my invention, I annex hereto three sheets of drawings, in which the same reference characters are used to designate identical parts in all the figures, of which—

Fig. 1 is a side elevation of a rotary engine and its associated elements included in the novel system;

Fig. 2 is a top plan view of the same, but with the pump omitted;

Fig. 3 is a central vertical section through the volatilizer, as seen on the line 3—3 of Fig. 4;

Figs. 4 and 5 are horizontal sections through the volatilizer as seen on the lines 4—4 and 5—5, respectively, of Fig. 3;

Fig. 6 is a detail showing another form of one of the volatilizer valves;

Fig. 7 is a central vertical section, on an enlarged scale, through the balanced controlling valve, seen in side elevation in Fig. 1;

Fig. 8 is a central vertical section on an enlarged scale on the line 8—8 of Fig. 2;

Fig. 9 is a section on a larger scale on the line 9—9 of Fig. 8;

Fig. 10 is a side elevation of a portion of the mechanism as seen from the right-hand side of Fig. 9;

Fig. 11 is a detail of a check valve associated with the fuel pump and seen on a smaller scale in Fig. 1; and

Fig. 12 is a perspective view of the end of an expanding ring associated with the vaporizer.

Referring first to Figs. 1 and 2, 40 is the rotary engine carried by the heavy base 41 having the rotor shaft 42, mounted in suitable bearings in the heads 43 and 44 of the cylinder. A sprocket wheel 45, secured on the shaft 42 between the head 43 and the fuel pump 46, mounted on the bracket 47 projecting from the head 43, drives

the sprocket chain 48, which drives the sprocket wheels 49 and 50 on the cam shafts 51 and 52 journalled in the head 43 and in the valve casings 53 and 54. The valve casing 53 has a short compressor outlet pipe 55 connected to the heating chamber 56, through which the compressed air passes, and which passes therefrom through the elbow 57 and connections hereinafter described to the vaporizer 58, where the fuel oil is vaporized by the combined action of heat and compressed air, and thence passes through the short pipe 59 to the balanced controlling valve 60, which in turn is connected to the elbow 61 which furnishes the mixture inlet to the valve casing 54. The fuel oil is drawn from its supply through the pipe 62 having the manually operated controlling valve 63 therein, and passes through the union 64 containing the check valve 65 to the inlet 66 of the rotary pump 46, by which it is forced from the outlet 67 through the pipe 68 to the heating coil 69 in the chamber 56, thence through the continuation pipe 70 to the inlet port 71 of the vaporizer 58. The ignition timer 72 may be secured on the valve shaft 52, as shown in Fig. 2.

As I intend to utilize the vaporizer 58 to act on different oils having different flash points, such as gasoline with its extremely low flash point, to crude oils having high flash points and needing high heat, it is essential to control the heating of the compressed air by the exhaust fumes. I will now describe how it is regulated. It will be understood that the compressing of the air prior to its delivery to the heater heats it considerably, but, especially for the heavy oils, it is necessary to increase the heat very much, and for this purpose I use the exhaust fumes from the motor. I have shown my present invention as applied to the motor shown in my Patent No. 2,162,861, dated June 20, 1939, where the motor and air compressor are combined, as it were, but it will be understood that it can be applied to other forms of motors, and that the motor and air compressor can be separate units, if desirable.

As before stated, the compressed air, heated somewhat by the compression, leaves the valve chamber 53 through the pipe 55, which, as seen in Fig. 8, is connected by the elbow 73 with the pipe 74 let into the center of the bottom plate 75 of the heating chamber 56, the cylindrical body of which is bolted between the bottom plate 75 and the top plate 76. A smaller metal cylinder 77 is secured centrally between the top and bottom plates. The fuel pipe 68 is connected by

the elbow 78 with a duplex helical coil 69 located in the cylinder 77 and emerging therefrom through the opening 79 into which the pipe 80 is threaded at its lower end, the upper end being threaded into the elbow 57 from which the horizontal pipe 81 extends into the port 84 of the vaporizer 58. The upper end of the duplex coil 69 passes through a gasket 82 in the elbow and is connected by the elbow 83 with a continuation 70 of the fuel pipe, which is threaded into the fuel entrance aperture 71 of the vaporizer 58. The exhaust from the engine discharges into the pipe 85 which extends beneath the heating chamber 56 to any desired outlet for the fumes. A vertical pipe 86, extending downward from the bottom plate 75, is let into the pipe 85, and an outlet pipe 87 is connected to the elbow 88 from which a pipe 89 leads the diverted exhaust fumes to any desired point of discharge. A swinging valve 90, carried by the shaft 91 journalled in the pipes 85 and 86 at their junction, is pressed against the lug 92 in the pipe 85 by the spiral spring 93 secured at one end to the shaft 91, and at the other end to the adjusting arm 94 fulcrumed on the end of the shaft 91 and having the spring-pressed pin latch 95 sliding therein and adapted to enter any one of the several apertures 96 located in the dial disk 97 secured to the pipes 85 and 86, as seen in Fig. 9. These apertures are respectively noted on the dial 97 as intended for adjusting the tension of the spring 93 for using the apparatus with various oils, such as gasoline, kerosene, distillate and crude oils, as obviously the further the handle 94 is turned clockwise, the greater the tension of the spring 93 and the more firmly the valve 90 will be held against the lug 92, in which position the bulk of the exhaust fumes will pass through the pipe 86 and out of the pipe 89, necessarily heating the compressed air in the cylinder 77, which in turn heats the fuel oil in the duplex coil 69. As the heat increases, this duplex coil expands downward and I have utilized it as an effective thermostat element by having its lower end rest on the disk or spider 98 on the vertical rod 99 which extends downward through the gasket 100 in the elbow 73, which gasket is adjusted so as to cause as little friction as possible on the rod 99, while preventing any serious leakage of the compressed air at that point. The lower end of the rod 99 is connected to the bell crank lever 101 fulcrumed on the lug 102 projecting downwardly from the elbow 73, whose other end is connected by the link 103 with the arm 104 secured to the other end of the shaft 91.

The operation of this novel thermostat mechanism will now be readily understood. The arm 94 is adjusted to the position required for the particular fuel to be used, and it will be understood that it may be swung around through more than 360 degrees, if necessary to secure the desired tension of the spring and the apertures 96 may be marked accordingly. The pressure of the spring 93 will hold the valve 90 against the lug 92, thereby diverting most, or any desired portion, of the exhaust fumes through the heating chamber 56. When the temperature approaches the limit set for the particular fuel, the rod 99 will be forced downward by the lengthwise expansion of the duplex coil 69, and the valve 90 opened to allow the necessary portion of the exhaust fumes to escape to the atmosphere without passing through the heating chamber 56. By experimentation, the tension of the spring can be adjusted satisfactorily to deal with

any grade of oil likely to be used for explosion engines.

Turning now to Figs. 1 to 6, the compressed air reaching the inlet 84, has been heated by 5 passing through the heated cylinder, and also additionally heated by the pressure to which it has been subjected, and as a consequence the fuel oil passing through the coil 69 in the heated compressed air in the chamber 56 is heated to 10 near the vaporizing point. It passes from the pipe 70 into the shallow circular chamber 187 formed in the cover 188 of the vaporizer 58. A disk 189 is secured between the cover 188 and the body of the vaporizer by the screws 190, 15 which also serve to secure between the disk 189 and the body 58 the annular packing ring 191. A domelike baffle plate 192 is supported by the arms from the interior of the lower part of the vaporizer 58, the bottom of which is concave, 20 as shown, so that any unvaporized oil that may run over from the baffle plate 192 will necessarily be directed to the outlet 193, having the seat therein for the upper end 194 of the float valve 195 in the float chamber 196. The lower end 25 197 of the valve cooperates with the seat 197a in the outlet 198 connected by the nut 199 with the pipe 200 leading to the union 64 connected to the inlet of the pump 46, so that any unvaporized oil will flow directly back to the pump and 30 not pass through the outlet 201 to the pipe 59, and thence to the engine. The pressure in the vaporizer will keep the float valve seated below and allow the unvaporized fuel oil to enter the chamber 196 until the oil therein rises high 35 enough to lift the valve 195 and allow the accumulated oil to flow back to the pump.

The disk 189 has therein a plurality, preferably five, of needle-valve seats 202, with which cooperate the needle valves 203 threaded through 40 the hubs of the rings 204 screwed into recesses 205 in the bottom of the cover 188. These recesses 205 have reduced circular openings 206 in the web forming the bottom of the chamber 187, these openings having their edges beveled to 45 form seats for the valves 207 formed on the lower ends of the sleeves 208 through which the bodies of the needle valves 203 extend, their upper ends being threaded and having thereon the nuts and set nuts 209 by which the tension 50 of the helically-coiled expanding springs 210 is regulated. The lower ends of these springs engage the tops of the short bearing sleeves 211 threaded into apertures 212 in the cover 188 and registering with the valve seats 206. The sleeves 55 208 have the shoulders 213 which engage the bottoms of the sleeves 211 when the valves 207 are seated. Secured on the sleeves 208 within the springs 210 are the collars 214 which have the tool holes 215 in their peripheries to insert 60 a tool to hold the sleeve 208 from turning when the nuts 209 are being adjusted to regulate the tension of the springs 210, which are set at different tensions so that the valves 207 will open at different pressures and allow the oil to pass the needle valves in fine streams and meet the compressed air entering the vaporizer. One of the valves 207 will be set to open at a minimum pressure produced by the engine running slowly, and three other valves 207 are set at increasing 65 pressures to open as the speed of the engine is increased by opening the fuel valve 83 wider, thereby increasing the pressure, the fifth one being set at the highest pressure and opening only as an auxiliary valve when the valve 63 is wide open and 50% air and 50% fuel oil is ad-

mitted. When a valve 207 is closed, the shoulder 213 seats against the bottom of its sleeve 211 to prevent leakage upward, and when it is wide open, the collar 214 seats against the top of the sleeve 211 for the same purpose. While the construction shown is simple and operative, I may prefer to use the construction shown in Fig. 6, where I omit the shoulder 213 and the collar 214 seating on the bottom and top of the short bearing sleeve 211, and I provide a cap 216 threaded on the bearing 215^a which prevents the fuel oil or compressed air from leaking in all positions of the valve and is also free of any friction that would necessarily be present if packing were used to prevent leaking. With this arrangement the tool hole 215^a will be placed directly in the sleeve 208^a, instead of in the omitted collar 214.

In order to distribute the compressed and heated air equally all around the inner periphery of the vaporizer 58 so that the fuel from each of the apertures 202 will be equally subjected to the action of the compressed and heated air, I form in the under side of the disk 189 an annular channel 217 which, when the engine is not running, is closed by the expanding ring 218 pressed upward against it by the plurality, preferably eight, of helically-coiled expanding springs 219 seated in the recesses 220 provided for them in the inwardly projecting flange 221 formed on the interior of the vaporizer 58, and preferably having the plane surface at its top to form a seat for the ring 218 when the latter is forced down to the limit by the highest possible pressure of the compressed air. As this ring is pushed down, the compressed air escapes, forming a sheet, as it were, that rushes toward the center and heats all the oil and air that is coming from the needle valves to an equal temperature, and because of the heated compressed air and the heated oil and air, both well toward the flash point of the latter, the vaporization is thoroughly effected.

The union 64 has the spring-pressed check valve 65, shown in section in Fig. 11, and the nuts 222, cooperating with the threaded upper end of the valve stem 223, enable me to adjust the tension of the spring 224 so as to draw in any desired percentage, preferably 50-50, of air to mix with the oil as it is delivered by the pump 46 to the vaporizer 58. The action of the heated fuel oil and air delivered by the pump 46, spraying past the needle valves 203 into the compressed air, serves thoroughly to vaporize the fuel oil and produce a mixture delivered under a high pressure to the engine, thus utilizing its thermal units in the most efficient manner possible.

To stop or start the engine with the pressure intact, and volatilized oil ready to start the engine on compression, I use the balanced valve 60, shown in detail in Fig. 7, where it will be seen that the two valve disks 60^a and 60^b are of substantially, although not quite, the same size, so that the pressure of the mixture passing therethrough will not offer much resistance either to its closing or subsequent opening.

While I have shown in Figs. 3, 4, 5 and 6, a novel carburetor, I do not herein claim the same, as it is claimed in my application No. 276,253, filed May 27, 1939, of which this application is an enforced division.

While I have shown and described my invention as embodied in the forms which I at present consider best adapted to carry out its purposes, it will be understood that it is capable of modifications, and that I do not desire to be lim-

ited in the interpretation of the following claims except as may be necessitated by the state of the prior art.

What I claim as new and desire to secure by Letters Patent of the United States is:

1. In a power generating system, the combination with an explosion engine and air compressor, of a vaporizer, a conduit leading from an oil supply to said vaporizer, means for forcing oil through said conduit, means for heating the oil as it passes through said conduit before it reaches the vaporizer, a thermostat controlled by the heat of the oil before it reaches the vaporizer, and connections from the thermostat to the heating means to modify its action when the heat of the oil approaches a certain predetermined degree before it reaches the vaporizer.

2. A power generating system as defined in claim 1, in which the heating means consists in part of a conduit leading from the compressor outlet surrounding a portion of the oil supply conduit.

3. A power generating system as defined in claim 1, in which the heating means consists in part of a conduit leading from the exhaust of the engine surrounding a portion of the oil supply conduit.

4. A power generating system as defined in claim 1, in which the heating means consists of a conduit leading from the compressor outlet surrounding a portion of the oil supply conduit, together with a conduit leading from the exhaust of the engine and in turn surrounding so much of the compressor conduit as surrounds the oil supply conduit.

5. A power generating system as defined in claim 1, in which the heating means consists of a conduit leading from the exhaust of the engine surrounding a portion of the oil supply conduit and in which said connections consist of a valve in the exhaust conduit between the exhaust outlet and where it surrounds the oil supply conduit, and connections from the thermostat to the valve to move it when the heat of the oil reaches the desired limit to shut off the exhaust gases from the conduit about the fuel conduit.

6. A power generating system as defined in claim 1, in which the heating means consists in part of a conduit leading from the compressor outlet and opening into the vaporizer, and surrounding a portion of the oil supply conduit.

7. A power generating system as defined in claim 1, in which the thermostat is formed by a part of the oil conduit which forms a duplex helical coil.

8. In a fuel vaporizer, the combination with a chamber adapted to receive a liquid fuel, of an associated chamber adapted to receive air under pressure, means for discharging the fuel in jets from the fuel chamber into the air chamber, means for heating the air and the fuel before they enter their respective chambers, a thermostat affected by the temperature of the air before it enters the air chamber, and connections from the thermostat to the heating means to reduce its action when the temperature of the fuel reaches a certain point.

9. A fuel vaporizer as defined in claim 8, which is provided with means for adjusting the temperature at which the thermostat will act.

10. A fuel vaporizer as defined in claim 8, in which the means for heating the air consists of

a conduit for the air passing through a conduit for exhaust vapors from an engine.

11. A fuel vaporizer as defined in claim 8, in which the liquid fuel is also heated by the same means before it enters the fuel chamber.

12. A fuel vaporizer as defined in claim 8, in which the means for heating the air consists of a conduit for the air passing through a conduit for exhaust vapors from an engine, and in which the liquid fuel is also heated by a conduit therefor passing through a portion of the air conduit.

13. In a gas engine, the combination with a volatilizer, of means for supplying oil thereto under pressure, means for delivering compressed air to the volatilizer, and means for heating the compressed air from the exhaust fumes of the engine which in turn heats the oil, all before the oil and compressed air reaches the volatilizer.

14. In a gas engine, the combination with a 20 volatilizer, of means for supplying oil thereto

under pressure, means for delivering compressed air to the volatilizer, means for heating the compressed air from the exhaust fumes of the engine which in turn heats the oil, all before the oil and compressed air reaches the volatilizer, and a thermostat controlling the application of the heat of the exhaust fumes to the compressed air to regulate the temperature at which the oil is delivered to the volatilizer.

15. In a gas engine, the combination with a volatilizer, of means for supplying oil thereto under pressure, means for delivering compressed air to the volatilizer, means for strongly heating the compressed air from the exhaust fumes of the engine, which compressed air in turn heats the oil before it enters the volatilizer, and a thermostat controlling the application of the exhaust fumes to regulate the temperature at which the oil is delivered to the volatilizer.

WILLIAM LISTER.
